UNITED STATES PATENT OFFICE.

LISLE C. WILLIAMS, OF MINNEAPOLIS, MINNESOTA.

DESIGN FOR A STEERING POST AND WHEEL FOR A COASTER.

59,944.

Specification for Design.

Patented Dec. 6, 1921.

Application filed July 11, 1919. Serial No. 310,283. Term of patent 3½ years.

To all whom it may concern:

Be it known that I, LISLE C. WILLIAMS, a citizen of the United States, residing at Minneapolis, in the county of Hennepin and State of Minnesota, having invented a new, original, and ornamental Design for a Steering Post and Wheel for a Coaster, of which the following is a specification, reference being had to the accompanying drawings, forming part thereof.

Figure 1 is a side elevation of the steering post and wheel; and

Fig. 2 is a front elevation thereof.

I claim:

The ornamental design for a steering post and wheel for a coaster, as shown.

LISLE C. WILLIAMS.
